CLOTHES WRINGER

Simon E. Schroeder, Chicago, Ill., assignor to
 Barlow & Seelig Mfg. Co., Ripon, Wis., a corporation of Delaware

Application December 13, 1935, Serial No. 54,282

35 Claims. (Cl. 68—253)

This invention relates to improvements in wringers especially adapted for use in connection with washing machines.

One object of the invention is to provide a wringer comprising cooperating pressure rolls, wherein the rolls may be quickly released by separation of the same when desired, or in case of emergency, with a minimum amount of effort on the part of the operator.

Another object of the invention is to provide in a wringer, as set forth in the preceding paragraph, means for automatically stopping rotation of the rolls upon release thereof.

A still further object of the invention is to provide means for automatically effecting release of the rolls of a wringer of the type indicated when the article which is being operated upon is accidentally wound about one of the rolls of the wringer or upon jamming of the rolls.

A more specific object of the invention is to provide a wringer comprising cooperating rolls with one of the rolls mounted in a frame arranged to be swung to move the roll carried thereby away from the cooperating roll, to effect release of the mechanism, wherein the swinging frame is effectively locked in position with the rolls in operative relation by simple and reliable means, and the means for locking the same may be instantaneously released by the operator through readily accessible and conveniently located actuating means.

Yet another object of the invention is to provide in a wringer of the type set forth means engaged and actuated by an article, which accidentally becomes wrapped about one of the rolls of the wringer, for quickly releasing the locking means of the swinging frame so that the frame is free to be displaced to a position to effect separation of the rolls.

Still another object of the invention is to provide in a roll type of wringer, wherein one of the rolls is held against the other by spring pressure, means for effecting separation of the rolls to remove the pressure and for again effecting restoration of the rolls to operative relation without any change in the adjustment of the pressure means.

A further object of the invention is to provide in a wringer having cooperating rolls and driving mechanism for rotating the rolls in reverse directions, which driving mechanism may be disconnected to stop the operation of the rolls, an operating lever or handle movable in reverse directions for controlling the operation of said driving mechanism to effect rotation of said rolls

in said reverse directions, and also movable to a neutral position to disconnect the driving mechanism and stop rotation of the rolls, wherein release of the driving mechanism and restoration of the operating handle to neutral position is automatically effected through means controlled by the operator for producing release of the rolls from operative relation.

Other objects of the invention will more clearly appear from the description and claims hereinafter following.

In the drawings, forming a part of this specification, Fig. 1 is a front elevational view of the improved wringer, the housing thereof being shown partly broken away to disclose certain interior parts.

Fig. 2 is a transverse, vertical, sectional view of the device shown in Fig. 1, certain parts being shown in elevation. Fig. 2a is a fragmentary sectional view, on an enlarged scale, illustrating certain parts at the upper left-hand corner of Fig. 2. Fig. 2b is a view similar to Fig. 2a, showing certain parts at the upper right-hand corner of Fig. 2.

Fig. 3 is a vertical, sectional view corresponding substantially to the line 3—3 of Fig. 2.

Figs. 4 and 5 are vertical, sectional views corresponding respectively to the lines 4—4 and 5—5 of Fig. 2, illustrating the parts in different positions.

Fig. 6 is a vertical, sectional view corresponding to the line 6—6 of Fig. 2.

Fig. 7 is a top plan view of Fig. 1, on a reduced scale.

Fig. 8 is a detailed, plan view of an operating cam and cooperating latch bar shown in Figs. 2, 2a and 6, the latch bar being broken away.

Figs. 9 and 10 are views similar to Fig. 3, with certain parts broken away and others omitted, and showing the mechanism in two different positions.

Fig. 11 is a vertical, sectional view corresponding to the line 11—11 of Fig. 2. Fig. 11a is a horizontal, sectional view corresponding substantially to the line 11a—11a of Fig. 11. Fig. 11b is a vertical, sectional view corresponding substantially to the line 11b—11b of Fig. 11a.

Fig. 12 is a detailed view of a certain locking plate shown in Figs. 2, 3, 9, 10, 11, 11a, and 11b.

Fig. 13 is a part horizontal sectional and part plan view corresponding substantially to the line 13—13 of Fig. 2.

Figs. 14, 15, and 16 are respectively enlarged broken views of the mechanism at opposite ends and at the central portion of Fig. 13.

Fig. 17 is an enlarged, vertical, sectional view similar to Fig. 2, but showing the mechanism at the right-hand end of Fig. 2 only and further illustrating the driving gear mechanism for the wringer in vertical section.

Fig. 18 is a horizontal, sectional view corresponding substantially to the line 18—18 of Fig. 17.

Fig. 19 is a view similar to Fig. 18, but showing the parts in a different position.

Fig. 20 is a vertical, sectional view corresponding to the line 20—20 of Fig. 18.

Fig. 21 is a view similar to Fig. 20, but illustrating the parts in different position.

Figs. 22 and 23 are vertical, sectional views corresponding respectively to the lines 22—22 and 23—23 of Fig. 19.

Fig. 24 is a detailed view of a certain latch plate shown in Figs. 17 to 23 inclusive.

Fig. 25 is a detailed, perspective view of the spring-pressed slide for restoring the controlling lever or handle to its neutral position.

Fig. 26 is a detailed view of a certain gear member operated by the controlling lever or handle for shifting the gear elements of the driving mechanism and for actuating the tilting drainboard.

Fig. 27 is a detailed view of the pin or rod for actuating the mechanism for disconnecting the power from the bottom roll of the wringer and restoring the controlling handle or lever to its neutral position.

Figs. 28 and 29 are views similar to Fig. 11, but showing the swinging frame which carries the top roll, in two different positions, said views being partly broken away.

Fig. 30 is a vertical, sectional view corresponding substantially to the line 30—30 of Fig. 17.

Fig. 31 is a horizontal, sectional view corresponding substantially to the line 31—31 of Fig. 2.

Fig. 32 is a vertical, sectional view corresponding substantially to the line 32—32 of Fig. 2.

In said drawings, A indicates the main or bottom frame, and B the swinging or top frame of my improved wringer. The main or bottom frame A includes a housing in the form of a heavy sheet metal stamping having spaced, vertical side walls 40—40, a transversely extending, central, troughlike section 41, and front and rear, downwardly and outwardly inclined walls 42—42, which form continuations of the front and rear walls of the troughlike section 41 and serve as fixed drainboard members. At opposite sides, the frame A is provided with centrally disposed, upstanding, supporting arms 43—43 by which the swinging frame is supported, as hereinafter more fully pointed out. The side wall members 40—40 to the front and rear of said arms 43—43 are raised with respect to the drainboard members 42—42, as clearly indicated at 44 and 44 in Figs. 1, 3, 6, 7, and 11. The side arm 43 at the right of Fig. 2 is lined with a casting 45, which is fixed to said arm in any well known manner. The side arm 43 at the left of Fig. 2 is also lined by a casting 46, which is secured to said arm. The castings 45 and 46 are provided with sleeve-like sections 47—47 adjacent to their upper ends, which are interiorly threaded. The arms 43—43 are provided with openings in alignment with the openings of the sleeve sections 47—47.

The swinging or top frame B includes a stamped heavy sheet metal housing 48 having spaced, vertical side walls 49—49, and front and rear spaced walls 50—50 connected by a curved top wall section 51. The central portion of the

housing 48 is contracted, as indicated at 52, to form a seat for a purpose hereinafter pointed out. To the inner faces of the side walls 49—49 are secured castings 53—53, which have sleeve sections 54—54 formed at the upper ends thereof, the openings of which are in substantial alignment with the openings of the sleeves 47—47 of the castings of the arms 43—43 of the main or bottom frame A.

10 A gear housing C is secured to the main frame A, as shown at the right in Figs. 2 and 17, which contains the mechanism for driving the bottom roll of the wringer. The housing C is in the form of a casting and has a depending sleeve section 55 thereon, which fits over the usual upstanding driving shaft housing of the washing machine. At the inner end, the housing C is closed by a cast plate 56, which has a central bearing sleeve 57 formed integral therewith.

20 The top and bottom rolls of the wringer are indicated by 58 and 59 respectively and are of the usual type provided with surfaces of rubber. The shaft of the bottom roll 59 is indicated by 60 and extends from opposite ends of said roll. The projecting shaft portions 60—60 are rotatably supported in bearing sleeves 61—61. The shaft section 60 at the right-hand side of Figs. 2 and 4 projects beyond the corresponding bearing sleeve 61 and is connected with the driving mechanism, as hereinafter more fully pointed out.

30 At opposite ends, the top and bottom rolls 58 and 59 are provided with intermeshing gears 62—62 and 62—62, which are fixed to the shafts of the rolls. Guard members 63—63 are provided at opposite ends of the rolls for properly guiding the material passed between the rolls and preventing the same from becoming engaged with the gears 62—62. Each guard member 63 is provided with a sleeve portion 64, which surrounds the bearing sleeve 61 at the corresponding side of the wringer and serves as supporting means for said bearing sleeve. The main portion of each guard member 63 embraces the corresponding gear 62 and a portion of the end section of the bottom roll 59 and has diverging arm portions 65—65 at the top thereof, which embrace the lower portion of the corresponding gear 62 of the top roll 58 and the end portion of said roll. The sleeve-like sections 64—64 of the guard members 63—63 are supported in bearing seats of vertically movable castings 66—66 at opposite sides of the lower or main frame A, which castings 66—66 are guided in ways 67—67 formed in depending extensions 68—68 of the castings 45 and 46 of the upstanding arms 43—43 of said main frame A.

40 The roll 59 is held in normal raised position by cam members 69—69 fixed to the transversely extending cam shaft 70, which has its opposite ends rotatably supported in bearing openings of brackets 71—71 secured to the flat bottom wall portions 72—72 of the trough-like section 41 of the main frame A and the extensions 68—68 of the castings 45 and 46 by means of cap screws 73—73, or any other well known equivalent securing elements.

50 The means for supporting the castings 66—66 in raised position, which includes the cam members 69—69 and connected parts, is not specifically claimed in this application and, therefore, needs no further detailed description, the same being fully described in detail in my copending application, Serial No. 54,283, filed December 13, 1935, now Patent No. 2,114,404, issued April 19, 60 70 75 1938. However it might be pointed out that the

cam members 69—69 are operated by an arm 74 at the outer end of the roll shaft 60 of the roll 59 at the left of Fig. 2, said arm engaging and cooperating with arm 75 on the cam shaft 70.

The top roll 58 is carried by the swinging frame B and has a shaft member having its opposite ends 76—76 projecting from the roll, said projecting shaft portions being journaled in two-piece bearing blocks 77—77 slidably guided for vertical movement in guideways 78—78 provided on the castings 53—53 of the swinging frame B. Each guideway 78 is formed by a pair of spaced, vertical flanges 79—79 formed on the corresponding casting 53.

The swinging frame B is pivotally supported on the upstanding arms 43—43 of the main frame A by trunnion members 80—80 fixed to said upstanding arms 43—43. The trunnion member 80 at the left of Fig. 2 is in the form of a headed screw secured within the threaded sleeve portion 41 of the casting 46 of the corresponding arm 43, the bearing portion of said trunnion member being of smaller diameter than the screw-threaded portion thereof and extending into the sleeve section 54 of the casting 53 at the corresponding side of the swinging frame B. The trunnion member 80 at the right of Fig. 2 is in the form of a cylindrical sleeve having a head at the outer end and a threaded section secured within the sleeve portion 41 of the casting 45 of the corresponding arm 43 of the main frame A. The journal portion proper of this trunnion 80 extends into the sleeve 54 of the casting 53 at the corresponding side of the swinging frame B. The heads of the trunnion members 80—80 are preferably of such a shape as to fit a wrench for manipulating the same.

The top roll 58 is carried within the swinging frame B by means which yieldingly forces this roll against the bottom roll 59, thereby permitting the roll 58 to lift upwardly to accommodate the article being passed between the rolls and yet maintain the proper pressure. The means for carrying the top roll 58, as most clearly shown in Figs. 2 and 31, includes two pairs of links 81—81 and 81—81 at opposite sides of the swinging frame B. The links 81—81 of each pair are pivotally connected at their lower ends to the corresponding bearing block 77 for the top roll 58. The pairs of links 81—81 and 81—81 are connected to pivoted lever plate members 82—82 and 82—82 arranged in pairs at opposite sides of the mechanism. The lever plate members 82—82 of each pair are disposed at opposite sides of the sleeve-like section 54 of the casting 53 at the corresponding side of the swinging frame B. As clearly shown in Fig. 2, each lever plate member 82 is of substantially triangular outline. The members 82—82 of each pair of plates are pivotally supported at their upper ends by a pivot pin 83 mounted in upstanding side wall sections 84—84 on the corresponding sleeve section 54. The links 81—81 of the corresponding pair are pivotally connected to the outer ends of the plate members 82—82, as indicated at 85—85. To the inner lower corners of each pair of lever plate members 82—82 are pivoted a pair of links 86—86 which serve to connect the lever plate members 82—82 with a follower 87, to which the opposite ends of these links are pivoted, as indicated at 88. The followers 87—87 are slidably carried on a shaft 89, which extends into the bearing sleeve sections 54—54 of the castings 53—53 at the opposite sides of the frame B and, as hereinafter pointed out, is employed to adjust the

tension of the springs which yieldingly resist upward movement of the top roll 58. These springs are two in number and are indicated by 90—90. Each spring 90 cooperates with one of the spring followers 87, said spring surrounding the shaft 89 and being interposed between the cooperating follower 87 and adjustable abutment means associated with the bearing sleeve section 54 of the casting 53 at the corresponding side of the swinging frame B. Each adjustable abutment means comprises a sleeve 91 splined to the shaft 89 and in threaded engagement with interior threads of the sleeve section 54, a follower disc 92 which abuts the spring 90, and a ball bearing element 93 interposed between the follower disc 92 and the outer end of the adjusting sleeve 91. The cooperating threads of the sleeve 91 and the sleeve section 54 at one side of the mechanism are left-hand, while the cooperating threads of the sleeve 91 and the sleeve section 54 at the opposite side are right-hand. As will be understood, rotation of the shaft 89 will thus effect movement of the adjustable spring abutment means at opposite sides of the mechanism in reverse directions. Rotation of the shaft 89 is effected by means of a hand wheel 94 connected to said shaft. The parts are proportioned so that the spring followers 87—87 normally abut each other, thereby limiting the expansion of the springs 90—90 and also limiting the downward displacement of the top roll 58 through the connecting links 86—86, 81—81, and the lever plate members 82—82. The limit of downward displacement of the roll 58 is such that it will have proper pressure contact with the roll 59 during the operation of the wringer. When an article is passed between the rolls 58 and 59, the roll 58 is forced upwardly against the resistance of the springs 90—90, the links 81—81 and 81—81, which are pivotally connected to the bearing blocks 77—77, being raised, thereby rocking the lever plate members 82—82 and 82—82 on their pivots 83 and 83 and effecting outward movement of the links 86—86 and 86—86 and pulling the followers 87—87 outwardly against the springs 90—90, compressing the latter against the adjustable spring abutments of the sleeve sections 54—54 of the castings 53—53 at opposite sides of the frame B.

To hold the swinging frame B in operative position with the top roll 58 centered above the bottom roll 59, latch means is provided, which is automatically locked when the frame B is properly centered. This latch means may be unlocked or released when desired and is automatically released under certain conditions. This latch means for locking the swinging frame B, as shown most clearly in Figs. 2, 2a, 2b, 3, 9, 10, 11, 12, and 17, comprises a pair of spring-pressed, sliding latch plates 95—95 mounted in the frame B, engaging a pair of keepers 96—96 on the main frame A. The keepers 96—96 are in the form of stampings located at opposite sides of the frame A and are secured to the castings 45 and 46. As most clearly shown in Figs. 2, 3, 9, 10, 11, 17, 28, and 29, each keeper stamping 96 comprises a vertical platelike section provided with a laterally inwardly outstanding flange 97. The flange 97 of each keeper is cut out at the center to provide a notch or seat 98 adapted to cooperate with the corresponding latch plate 95. The keepers are fixed to the castings 45 and 46 by screws, or any other equivalent securing means extending through the plate sections of said keepers and into the castings 45 and 46. As most

clearly shown in Figs. 3, 9, 10, and 11, the flange 97 of each keeper is inclined upwardly and outwardly away from the notch or opening 98, being preferably upwardly curved, the curvature thereof being concentric with the axis of swinging movement of the frame B. The walls of the flange 97 at the opening 98 are bent downwardly to give a tapered formation to the seat or opening 98.

The two latch plates 95—95 are of similar design. One of said plates is shown in detail in Fig. 12. As shown in Fig. 12, the plate 95 is of substantially rectangular outline, having a projecting locking tongue 99 at the lower end, said tongue being rounded off, as shown. The upper corners of the plate are preferably cut away and said plate is centrally slotted at the upper end, thereby providing two upstanding, spaced arms 100—100. The slot of the plate 95 is enlarged laterally, as indicated at 101, to provide clearance for the corresponding trunnion 80, which extends therethrough. The lower wall of the slot forms a seat 102 for the cooperating spring.

As shown most clearly in Figs. 2, 3, 11, and 17, the latch plates 95—95 are slidably mounted in vertical guideways 103—103 in the castings 53—53 of the swinging frame B. The guideway 103 of each casting 53 is formed on the outer side thereof, which abuts the corresponding side wall 49 of the swinging frame B. The plate 95 is thus guided between said side wall and the opposed wall of the guideway. Each latch plate 95 is yieldingly pressed downwardly by a spring 104 seated at its upper end in a pocket 105 in the casting 53 and having its lower end bearing on the spring seat 102 at the lower end of the slot in the plate 95. The narrow upper portion of the slot of each plate 95 is of substantially lesser width than the diameter of the corresponding trunnion member 80, thereby limiting the downward movement of the plate. In other words, the top wall portions of the enlarged section 101 of the slot engage the top of the corresponding trunnion 80, thereby acting as limiting stops for the plate 95. The lower ends of the plates 95—95 extend through openings in castings 106—106 at opposite sides of the bottom portion of the frame B. The castings 106—106, as most clearly shown in Figs. 2, 3, 9, 10, 11, 28, and 29, have inwardly offset, depending flanges 107—107. Each casting 106 is secured to the bottom portion of the corresponding casting 53 of the frame B and spans the opening below the bearing block 77 for the roll 58. The depending flange 107 of each casting 106 has the lower edge thereof curved, as shown in Figs. 3, 9, and 10. The curved flanges 107—107 engage between the arms 65—65 and 65—65 of the guard members 63—63 to swing the guard members on the bearing seats of the supporting castings 66—66 about the shaft 60 of the bottom roll 59 when the top frame B is swung to either side of centered position and also to center these guard members. In other words, the projecting curved flanges 107—107 of the castings 106—106 serve as centering means for the guard members.

When the frame B is in operative centered position, the tongues 99—99 of the plates 95—95 are seated in the openings 98—98 of the keepers 96—96 and are held in that position by locking means, hereinafter more fully described, cooperating with the latch plates 95—95 and holding the same against upward movement. When

the locking means is released, the plates 95—95 may be forced upwardly against the tension of the springs 104—104. Thus when the swinging frame B is moved to either side of the centered position, the tongues 99—99 of the latch plates 95—95 will ride up on the curved walls of the openings 98—98 of the keepers 96—96 and into engagement with the top faces of the flanges 97—97. As will be evident, when the locking means for the latch plates is released, the frame B may be swung to either side of centered position but is held rigidly locked when the latch plates are locked against upward movement with the tongues 99—99 thereof seated in the openings 98—98 of the keepers. It is further pointed out that the rounded locking tongues 99—99 act to cam the latch plates 95—95 upwardly by engagement with the outer edges of the portions 68—68 of the castings 45 and 46 of the main frame A when the frame B is being swung back to centered position after having been moved to either side with the tongue entirely clear of the casting sections 68—68 of the main frame A. The plates 95—95 will thus be positioned so that the tongues 99—99 thereof will again register with the guide flanges 97—97 of the keepers 96—96 to again be seated in the openings 98—98 of the keepers when the swinging frame B is brought to centered position. Inasmuch as the plates 95—95 are forced yieldingly downwardly by the springs 104—104, the tongues 99—99 of the plates will serve to accurately center the swinging frame B above the bottom roll 59 and maintain the same in such position when the latch plates 95—95 are locked against upward movement.

To lock the latch plates 95—95 in latching position, a sliding locking bar 108 is provided. This locking bar also forms part of the means for releasing the latch plates 95—95. As shown most clearly in Figs. 2, 3, 4, 9, 10, 11, 13, 14, 15, 16, and 17, the bar 108 is slidably guided in ways 109—109 in the castings 53—53, said ways being defined by the spaced walls 84—84 of the sleeve 54 of each casting 53. As shown in Fig. 2, the bar 108 is arched near the opposite ends thereof, as indicated at 110—110 to clear the pivot pins 83—83 of the levers 82—82. Upon referring to Figs. 13, 14, and 15, it will be seen that the bar 108 has a tongue 111 at the left-hand end and is notched at opposite sides of the right-hand end, as indicated at 112—112. Bearing rollers 113—113 are provided at opposite sides of the swinging frame B, which engage the upper side of the bar 108 to maintain the same seated in the ways 109—109. A U-shaped frame 114 is fixed to the bar 108 between the ends thereof and cooperates with certain cam means, hereinafter described, to move the bar to unlocking or releasing position. The U-shaped frame 114 has depending side arms and a horizontal top connecting section, which is disposed above the bar 108. The frame 114 is fixed to the bar 108 by means of screws, or any other well known securing elements, extending through the bar and into the top connecting section of the frame 114. A spring abutment plate 115 is fixed to the top of the frame 114, as most clearly shown in Fig. 2. This plate is also held by the screws which secure the bar 108 to the frame 114. A coil spring 116 urges the frame 114 and the bar 108 to the left, as viewed in Fig. 2. This spring is interposed between the upturned right-hand end of the plate 115 and a downwardly bent lug 117 on the top wall of the swinging frame B. Movement

of the bar 108 to the left is limited by engagement with a rotary cam member 118, Figs. 6 and 8 hereinafter more fully described. In Figs. 2 and 13, the bar 108 is shown in the extreme left-hand position and locks the latch plates 95-95 against upward movement. In this position, the wide end portion at the right-hand end of the bar 108, as viewed in Fig. 13, and the wide portion of the bar immediately adjacent to the tongue 111 at the left-hand end are disposed directly above the arms 100-100 of the plates 95-95 and engaged thereby. As will be evident, the latch plates 95-95 are thus held positively against upward movement and securely lock the swinging frame B in centered position above the bottom roll 59 of the wringer. When the bar 108 is moved to the right against the resistance of the spring 116 to bring the notches 112-112 and the tongue 111 thereof in the path of vertical movement of the latch plates 95-95, the latch plates are unlocked and are free to be forced upwardly against the resistance of the springs 104-104, clearance for the arms 100-100 and 100-100 of the latch plates 95-95 being provided by the notches 112-112 and the tongue 111 of the bar 108.

Two separate and independent actuating means are provided for operating and locking the bar 108 to move the same to releasing or unlocking position, one of said means being carried by the swinging frame B and the other by the fixed main frame A.

The actuating means, which is carried by the swinging frame B, comprises a saddle member 119 of substantially U-shaped cross section, adapted to rock on the frame B, and a cam plate member 120 actuated by said saddle member 119. Upon reference to Figs. 2, 3, 4, 5, 9, 10, and 13, it will be seen that the saddle member 119 is engaged over the central portion of the swinging frame B and is seated on the contracted portion 52 of said frame B. The saddle member 119 is mounted for rocking movement on the frame B and is normally yieldingly held in spaced relation to the side walls of the frame B. As shown most clearly in Figs. 2, 3, 4, and 5, the saddle member 119 is supported on the top wall of the central portion of the frame B by a pair of rocking supports 121-121 having tongues 122-122 extending through openings 123-123 in the top wall of the frame B. As shown in Figs. 3, 4, and 5, each support 121 has substantially flat bottom edge faces 124-124 at opposite sides at the inner end of the tongue 122. These faces 124-124 normally engage the upper wall of the frame B adjacent to the openings 123-123. To yieldingly maintain the saddle member 119 in normal centered position, as shown in Fig. 3, and to return the same to said normal position, a coil spring 125 cooperating with each support 121 is interposed between the top wall of the frame B and a pin 126 extending through the lower end of the tongue 122 of the corresponding support 121. The saddle member 119 may be rocked to either side of the centered position shown in Fig. 3 against the resistance of the springs 125-125, as shown in Figs. 4 and 5, and will be returned through the action of said springs 125-125 to the normal position shown in Fig. 3 as soon as the force which has displaced the saddle member 119 has been removed.

The cam plate member 120 is made in two parts, as clearly shown in Fig. 3. The same is disposed between the side walls of the U-shaped saddle member 119 and extends through open-

ings 127-127 provided in the opposite walls of the frame B. The cam plate 120 is fixed to the saddle member 119 to be moved therewith and cooperates with the side walls of the frame 114 to cam the same to the right, as viewed in Figs. 2 and 13. The cam plate 120 has reversely inclined cam faces 128-128 at opposite ends thereof, which respectively engage with the corresponding edges of the side walls of the frame 114.

A plate 129, which extends lengthwise of the frame B, that is, parallel to the axis of the top roll 58 of the wringer, is fixed to the bottom of the cam plate 120. A single bolt 130 extending through the plate 129 and the two sections of the cam plate 120 serves to secure these parts together. The plate 129 is provided with a depending, longitudinally extending rib 131 for a purpose hereinafter pointed out.

The operation of the locking and releasing bar 108, as controlled by the rocking saddle member 119, is as follows: With the roll 58 centered above the roll 59 and the latch plates 95-95 held in locking engagement with the keepers 96-96 by means of the locking bar 108 engaging over the upper-ends of the latch plates 95-95, the operator pushes against either side of the rocking saddle 119, thereby moving the cam plate 120 in either direction and camming the frame 114, together with the bar 108 which is fixed thereto, to the right, as viewed in Figs. 2 and 13, bringing the bar 108 to releasing position. When this releasing action has been effected, the top frame B will be automatically swung through the action of the intergeared rotating rolls 58 and 59, thereby effecting separation of the rolls and release of the pressure between the same. In this connection, it is pointed out that the top frame B may also be swung from its centered position by the operator during the operation of pushing on the side of the saddle 119.

The locking bar 108 is also released from locking engagement with the latch plates 95-95 by jamming of the wringer through an article accidentally becoming wound about the top roll 58. When an article is thus wound about the roll 58, the ribbed plate 129 will be engaged by said moving article and shift the cam plate 120 in the direction of rotation of the roll 58, thereby shifting the frame 114 and the bar 108 to release the latch plates 95-95 in the manner hereinbefore described so that the frame B may be swung from its centered position. Restoration of the locking bar 108 and frame 114 to normal position is effected by the spring 116 after each releasing action. By engagement of the frame 114 with the cam faces of the plate 120, the latter, together with the rocking saddle member 119, is restored to normal position. In this connection, it is further pointed out that the centering springs 125-125 for the saddle member 119 are also active in effecting restoration of the saddle member 119 and cam plate 120 to normal position.

The means hereinbefore referred to, which is mounted on the frame A for actuating the locking bar 108 to release the same, is most clearly shown in Figs. 2, 6, 7, and 8, and comprises the rotary cam 118 hereinbefore referred to, a slide bar 132 actuated by a pair of levers 133-133, and finger pieces or push buttons 134-134 operating the levers 133-133. The cam member 118, as shown in Figs. 6 and 7, is in the form of a disc having an outstanding cam flange 135 provided with an inclined face 136, most clearly shown in Fig. 8, which engages with the tongue 111 of the bar 108. The cam member 118 is

rotatably journaled on a cylindrical bearing portion 137 provided on the casting 46 at the left-hand side of the main frame A. Rotary movement of the cam member 118 is limited by means of a stop screw 138 fixed to the casting 46 and projecting through a slot 139 of the cam member 118. The sliding bar 132 is guided for vertical movement in a guideway 140 provided in the casting 46. As shown in Fig. 6, sufficient clearance is provided between the side walls of the guideway 140 and the sliding bar 132 to permit slight lateral rocking of said bar. The upper end portion of the sliding bar 132 is laterally offset and has its upper end pivotally connected to the cam member 118 by a pivot pin 141. A spring 142 interposed between an outstanding abutment lug 143 on the casting 46 and a shoulder 144 at the offset portion of the bar 132 yieldingly opposes upward movement of said bar. At the bottom end, the sliding bar 132 is provided with a T-shaped head 145. The levers 133—133 are pivoted on opposite sides of the casting 46 of the frame A, as clearly shown in Fig. 6. Each lever 133 has an inwardly extending short arm 146, which engages beneath the head 145 of the sliding bar 132, and a long arm 147, which is slotted at the outer end, as indicated at 148. Each lever 133 is pivotally supported on a pin 149 fixed in said casting 46. The finger pieces or push buttons 134—134 are mounted at the front and rear of the frame A so as to be readily accessible to the operator from either side of the wringer. Each finger piece or push button 134 comprises a head member projecting through an opening 150 in the wall of the frame A and a flange 151 at the inner end of the head member engaging with said wall of the frame A to limit outward movement of the head member. Each finger piece 134 is also provided with a depending stem 152 having a pin 153 at the lower end thereof working in the slot 148 of the corresponding lever.

The finger pieces 134—134 may be independently operated, and downward pressure on either finger piece will cause the corresponding lever 133 to be swung on its pivot, thereby raising the slide bar 132 against the tension of the spring 142 and rotating the cam member 118 in a contra-clockwise direction, as viewed in Fig. 6. Rotation of the cam 118 forces the bar 108 to the right, as viewed in Figs. 2 and 13, by action of the cam face 136 on the tongue 111 of said bar, thereby unlocking the latch plates 95—95 and permitting the frame B to be swung to a released position, as hereinbefore described. After either of the finger pieces 134—134 has been actuated, the spring 142, which cooperates with the slide bar 132, effects return of the finger pieces to the normal position shown in Fig. 6. Return movement of the slide bar 132 also rotates the cam 118 back to its normal position. When the parts have been thus returned to normal position, the cam portion of the cam member 118 is disposed so that the bar 108 may be returned to locking position with respect to the latch plates 95—95 by the spring 116, as hereinbefore pointed out.

From the preceding description, it will be evident that the means for operating the releasing mechanism for the latch plates 95—95 and unlocking the swinging frame B is conveniently located so as to be readily accessible from either the front or the rear of the wringer, one of the finger pieces 134 being located at the front and the other at the rear of the wringer, and the rocking saddle member 119 being accessible from both the front and rear of the wringer.

As hereinbefore pointed out, the wringer rolls 58 and 59 are intergeared and rotate in unison, the bottom roll 59 being shown as connected to the power-actuated driving gearing of the wringer. The driving gearing is arranged and designed so that the roll 59 may be driven in either right-hand or left-hand direction, as desired by the operator. This driving gearing is further arranged and designed so that the power 5 may be disconnected at will by the operator or disconnected automatically when the rolls 58 and 59 are separated by swinging movement of the frame B to either side of the centered position. The driving gearing is contained in the housing 10 C, which is fixed to the right-hand side of the frame A, as shown in Figs. 1, 2, 17, 18, and 19. A sleeve-like member 153 is journaled in the bearing opening of the sleeve 57 of the plate 56, which as hereinbefore described forms the inner wall 15 of the housing C. The sleeve 153 is provided with a radially extending arm 154 having a short arc-shaped section 155 at the outer end. The arc-shaped section 155 has gear teeth on the inner side thereof, which form a short rack member 156 cooperating with the operating handle lever 157, as hereinafter more fully described. The sleeve 153 is lined with a tubular brass or other metallic anti-friction bushing 158. In said bushing is journaled the hub portion 159 of a gear member 160. The hub portion 159 is hollowed out to provide a socket, as shown most clearly in Figs. 17, 18, and 19. The inner or bottom wall of the socket of the hub portion 159 is provided with a central outstanding lug 161. The lug 161 is of angular cross section and outwardly tapered. The end of the shaft 60 of the roll 59 is connected to the lug 161 by a coupling sleeve 162 having a portion of angular, internal cross section engaged over the lug 161 in driving relation. The other end of the coupling sleeve 40 162 is also of angular, internal cross section and is telescoped over the end portion of the shaft 60, which end portion is also of angular cross section so as to fit said sleeve in driving relation. 45 The sleeve 162 forms a flexible connection between the shaft 60 and the gear 160, thereby permitting the raising and lowering of the roll 59 with respect to the gear 160 and the frame A of the wringer. 50 The gear mechanism in the housing C is driven by the driving elements of an associated washing machine in the usual well known manner. In this connection, it is pointed out that the sleeve 55 of the housing C telescopes over the usual 55 vertically arranged, hollow standard of a washing machine, which standard has a vertically disposed shaft therein operatively connected to and rotated by the driving elements of the washing machine in a well known manner. This shaft extends beyond the standard and into the gear housing of the associated wringer and is coupled to the gearing of the wringer by a splined or similar connection. The top portion of such a vertical shaft is indicated at 163 in Figs. 17 to 60 23 inclusive of the drawings. The shaft 163, as shown, is provided with a plurality of vertically extending, radial ribs 164—164. A cylindrical sleeve-like gear member 165 is telescoped over the upper end portion of the shaft 163, the sleeve 65 member 165 being provided with internal vertical grooves, within which the ribs 164—164 of the shaft 163 engage. The sleeve 165 is thus mounted on the shaft for rotation therewith and vertical sliding movement thereon. At the upper and 70 lower ends, the sleeve member 165 has beveled 75

gear members 166 and 167 formed integral therewith. The section of the sleeve between the gear members 166 and 167 is enlarged, as shown in Figs. 17, 18, 19, and 23, said enlarged portion being provided with a plurality of annular rack teeth 168 for a purpose hereinafter pointed out. The sleeve member 165 is rotatably supported in a cylindrical, vertical bearing opening 169 in a casting 170 fixed to the housing C and has vertical sliding movement in said opening. The beveled gear members 166 and 167 cooperate with the teeth of the gear 160 to drive the latter in reverse directions.

Sliding movement of the gear member 165 on the shaft 163 is effected by a spur gear 171 fixed to the inner end of a horizontally disposed, short shaft 172 rotatably mounted in a bearing opening 173 in the housing C. The shaft 172 has the operating handle or lever member 157, hereinbefore referred to, formed integral therewith. The spur gear 171 meshes with the rack teeth 168 of the sleeve-like gear member 165, the casting 170 being cut away, as indicated at 174, most clearly shown in Figs. 18 and 19, to accommodate said spur gear. As will be evident, swinging movement of the handle member or lever 157 will effect rotation of the spur gear 171, which in turn effects sliding movement of the sleeve gear member 165 to shift the latter up or down in accordance with the direction of movement of the lever 157. The gear member 165 may thus be shifted to engage either the upper beveled gear 166 or the lower beveled gear 167 with the teeth of the gear 160, or to bring the gear member 165 to the neutral position shown in Fig. 17, where both beveled gears are disengaged from the gear 160, thereby disconnecting the driving means from the wringer rolls. Inasmuch as the beveled gears 166 and 167 respectively engage with the teeth at opposite sides of the gear 160, they effect rotation in respectively reverse directions of the gear 160 and the roll 59. As will be obvious, when both beveled gears 166 and 167 are disengaged from the gear 160, rotation of the roll 59 together with the roll 58 will be stopped.

Spring-pressed-latch means is provided to hold the gear member 165 in its three positions of adjustment, that is, the raised position when the gear 166 is engaged with the gear 160, the lowered position when the gear 167 is engaged with the gear 160, and the central or neutral position when both gears are disengaged. This latch means comprises a spring-pressed plunger 175 cooperating with the spur gear 171. The plunger 175 is slidably mounted in a pocket 176 in the housing C adjacent to the shaft 172 of the lever 157, and is urged toward the spur gear 171 by a spring 177 seated in the pocket 176. The spur gear 171, as most clearly shown in Figs. 18, 19, and 26, is provided with three spaced seats 178, 179, and 180, within which the rounded end of the plunger 175 is adapted to engage. With the plunger 175 engaged in the central seat 179, the gear member 165 is held in the neutral position, as shown in Figs. 19, 22, and 23; with the plunger engaged in the upper seat 178, as shown in Figs. 18 and 20, the gear 165 is held in the position shown in Fig. 20 so that the beveled gear 166 engages the teeth of the gear 160 at the upper side of the latter; and with the plunger engaged in the lower seat 180, as shown in Fig. 21, the gear 165 is held in the position shown in said last named figure and the beveled gear 167 is engaged with the teeth at the lower side

of the gear 160. The spur gear 171 also meshes with the gear teeth on the arm 154 of the sleeve 153, as shown in Figs. 18 to 23 inclusive, to oscillate the latter for a purpose hereinafter pointed out.

On the side of the spur gear 171 opposite to that engaged by the plunger 175, an arc-shaped flange 181 concentric with the axis of rotation of the gear is provided, having substantially flat end faces 182-182, which are in transverse alignment. These flat faces act as abutments or stops, which cooperate with a spring-pressed slide 183 for moving the operating handle lever 157 and the gear member 165 to neutral position, as hereinbefore pointed out. The abutment faces 182-182 are disposed so that they lie in a vertical plane when the operating handle or lever 157 is in said neutral position, as shown in Figs. 22 and 23. In this connection, it is pointed out that the operation of restoring the gear member 165 and the operating lever 157 to neutral position by means of the slide 183, thereby stopping rotation of the wringer rolls 58 and 59, is automatically performed whenever the swinging frame B is moved to either side of the centered position. The slide 183 is mounted for horizontal sliding movement in a guideway 184 provided in the casting 170, the guideway being closed by a cover plate 185. As shown most clearly in Figs. 18, 19, and 25, the end of the slide 183, which cooperates with the spur gear 171, is offset with respect to the main body portion of said slide and has a pair of outstanding spaced fingers 186-186 adapted to engage with the flat abutment faces 182-182 on the spur gear 171. At the opposite end, the slide 183 has a right-angular section 187 terminating in an outturned angular lip 188. At the bend between said section 187 and the lip 188, a beveled or inclined face 189 is provided for a purpose hereinafter pointed out. A pair of coil springs 190-190 are interposed between the section 187 of the slide 183 and the opposed wall of the housing C. These springs serve to force the slide 183 toward the spur gear 171. A swinging latch plate 191 cooperates with the slide 183 to lock it in the position shown in Fig. 18. As shown most clearly in Figs. 17, 18, 19, and 24, the body of the plate 191 is provided with a pair of openings 192-192, which engage over reduced end portions of a pair of bosses 193-193 on the outer end wall of the housing C, to anchor said plate for rocking movement. The plate 191 is held in position on the bosses 193-193 by an outstanding rib 194 on the casting 170, as shown most clearly in Figs. 18 and 19. The plate 191 is further provided with an upper, relatively short arm 195 and a lower, longer arm 196, which arms are inclined with respect to the portion of the plate which is rockingly supported on the bosses 193-193. The long arm 196 has a right-angular portion 197 near the outer end thereof forming a shoulder adapted to engage the beveled face 189 of the slide 183. Outwardly of the shoulder of the arm 196 is provided a lip 198, which bears on a spring 199 which yieldingly forces the plate 191 toward the corresponding side of the slide 183. As shown in Figs. 18 and 19, the spring 199 is interposed between the outer wall of the housing C and the lip 198 of the arm 196 of the plate 191. The latch plate 191 locks the slide 183 in the retracted position shown in Fig. 18 when the shoulder 197 of said latch plate is engaged with the inclined face 189 of the slide 183. When the latch plate 191 is swung out of latching engagement with said slide 183, the latter will be forced

upwardly to the position shown in Figs. 19 and 22 by the action of the springs 190—190, thereby rotating the spur gear 171, together with the operating lever 157, to the neutral position shown in Figs. 19, 22, and 23, by engagement of one of the fingers 186 of the slide 183 with the cooperating abutment face 182 of the flange 181 of the spur gear. As will be clear upon reference to Figs. 20, 21, and 22, the arrangement of the abutment faces 182—182 on the spur gear 171 and the cooperating fingers 186—186 on the slide 183 is such that the slide 183 in its forward movement will restore the parts to neutral position from either of the positions shown in Figs. 20 and 21.

The latch plate 191 is automatically tripped by a sliding pin or rod 200 when the frame B of the wringer is swung to either side of its centered position, the pin being projected against the short arm 195 of the latch plate 191 by movement of said frame. The pin 200 is slidably supported in suitable openings provided in the cast plate 56 of the housing C and in the corresponding side wall of the frame A. Cam means is provided on the swinging frame B for actuating the pin 200, said cam means being in the form of inclined cam faces 201—201, Figs. 11a, 11b and 17, on the casting 106 of said frame and the latch slide 95 at the corresponding side of said swinging frame B. The short arm 195 of the swinging latch plate 191 is engaged by the outer end of the pin 200 when the swinging frame B is moved to either side of centered position, thereby rocking the latch plate 191, disengaging the shoulder thereof from the slide 183 and permitting the slide 183 to be projected upwardly. When the swinging frame B is again centered, the pin 200 will be restored to its normal position by the return movement of the plate 191 through the action of the spring 199. It will thus be seen that by displacement of the swinging frame B to either side of its centered position the slide 183 will be released, thereby rotating the spur gear 171 and the mechanism connected therewith to neutral position. The operating handle or lever 157 is thus restored to its vertical position, as shown in Figs. 17, 19, 22, and 23, and the beveled gears restored to the neutral position where both gears are disengaged from the gear 160, thereby stopping rotation of the rolls of the wringer. When the operating lever 157 is swung to either side of its neutral position, the slide 183 will be forced downwardly by means of one of the abutments 182 engaging the corresponding finger 186 of the slide 183, thereby restoring the slide to the position shown in Fig. 18 and permitting the latch plate 191 to snap over the shoulder formed by the beveled face 189 of said slide 183. At the same time that the slide 183 is restored by moving the handle or lever 157 to either side of its neutral position, the gear member 165 will be shifted by the spur gear 171 bringing one of the beveled gears of the member 165 into operative driving engagement with the teeth of the gear 160. Rotary movement will thus be imparted to the bottom roll 59 in either a right-hand or left-hand direction, depending upon which beveled gear has been engaged with the gear 160.

In order to carry off any water which may drain through the bottom of the frame A, a tilting board 202 is provided. As shown most clearly in Figs. 17 and 30, the drainboard 202 has upstanding end sections 203—203, by which it is tiltingly supported on the cam shaft 70, the latter passing through openings 204—204 in said

upstanding sections. The upstanding section at the right-hand end of the drainboard 202, as seen in Fig. 17, terminates in an outturned flange 205. The tilting of the drainboard is effected through operation of the lever 157 in shifting the gears of the driving means, the sleeve 153, which is rotated by the spur gear connected to the operating lever 157, being provided with a pair of diametrically opposite lugs 206—206 at the inner end of said sleeve 153 which cooperate with slide plates 207—207 engaging the flange 205 of the tilting drainboard 202. The sliding plates 207—207 are provided at their upper ends with elongated slots, which fit over the lugs 206—206, thereby operatively connecting these plates to the sleeve 153. The lower end of each plate 207 is reduced in width to provide a finger 208. The fingers 208—208 of the plates 207—207 are guided in openings provided in a supporting bracket 209 secured to the corresponding side wall of the main frame A. The supporting bracket 209 is further provided with a pair of upstanding lips 210—210, which engage the outer sides of the plates 207—207 and maintain the plates in position on the lugs 206—206 of the sleeve 153. As will be evident, when the operating handle or lever 157 is moved to one side or the other of its neutral position, the sleeve 153 will be oscillated, thereby depressing one of the fingers 208 and rocking or tilting the drainboard 202 to properly shed the water.

To start the operation of the wringer, the control lever or handle 157 is swung in the proper direction from the vertical or neutral position shown in Figs. 1, 2, 17, 19, 22, and 23, to engage the beveled gear 166 or 167 with the gear 160, thereby rotating the rolls 58 and 59 in the desired direction. At the same time, the operating lever 157 effects tilting of the drainboard 202 through operation of one of the fingers 208 by movement of the sleeve 153 by the spur gear 171.

To at any time stop the wringer, it is merely necessary to return the control lever to the normal position, thereby disconnecting the gearing of the driving means. If the rolls of the wringer should become jammed, or in case it is desired to stop the operation of the wringer in an emergency, the rotation of the rolls may be stopped and the pressure on the rolls released by operating either of the finger pieces 134—134 or the rocking saddle member 119. As hereinbefore pointed out, depression of either of the finger pieces will release the locking mechanism for the latch plates 95—95, which hold the top roll 58 in centered position above the bottom roll 59. Similarly, operation of the saddle member 119 through slight pressure applied to either side thereof will effect release of the latch plates 95—95. Immediately upon the latch plates being released, the swinging frame B is automatically swung to one side of the centered position through the forces reacting between the two rotating rolls 58 and 59. The swinging frame B is thus displaced from the centered position in Fig. 3 to either the position shown in Figs. 9 and 28 or that shown in Figs. 10 and 29, depending upon the direction of rotation of the rolls 58 and 59, the latch plates 95—95 being cammed out of engagement with the locking openings of the keepers 96—96. Immediately upon the swinging frame B being moved from its centered position, the pin 200 will be projected to the right, as viewed in Figs. 2 and 17, thereby releasing the latch plate 191 from the slide 183 to shift the gear member 165 to neutral posi-

tion, disengaging the latter from driving relation with the gear 160 and stopping rotation of the rolls 58 and 59. In this connection, it is again pointed out that the releasing operation of the rolls and the driving mechanism of the wringer is also automatically effected in case of emergency when an article of clothing is wound about the top roll 58 and comes into engagement with the plate 129 of the saddle member 119 to actuate the latter.

To restore the parts to operative relation, the swinging frame B is manually swung back to its centered position, thereby bringing the latch plates 95-95 into latching engagement with the openings of the keepers 96-96. When the parts have been thus restored, the latch plates 95-95 are automatically locked in position against upward movement by the bar 108, as hereinbefore described. As is obvious, restoration of the slide 187 to its normal position, as shown in Fig. 18, is effected when the operation of the wringer is again started by manipulation of the lever 157.

I have herein shown and described what I now consider the preferred manner of carrying out my invention, but the same is merely illustrative and I contemplate all changes and modifications that come within the scope of the claims appended hereto.

I claim:

1. In a wringer, the combination with a pair of cooperating rolls operating under pressure; of means for supporting said rolls in operative opposed relation with the axes thereof in parallel relation in a common plane; driving means for said rolls; means controlled by the operator for displacing one of said rolls with respect to the other to either side of said common plane to release said rolls from operative engagement; and means operated through release of said rolls in either of said directions for disconnecting the driving means and stopping rotation of said rolls.

2. In a wringer, the combination with a pair of cooperating rolls operating under pressure; of driving means for said rolls; a trip means in opposed relation to the operating surface of one of said rolls engageable by an article wound about said roll and actuated by said article to release the rolls; and means automatically operated through release of said rolls for disconnecting the driving means and stopping operation of said rolls.

3. In a wringer, the combination with a pair of cooperating rolls operating under pressure; of driving means for said rolls; trip means in opposed relation to the operating surface of one of said rolls adapted to be engaged and actuated by an article accidentally wrapped about said roll for automatically separating the rolls to relieve the pressure therebetween.

4. In a wringer, the combination with a pair of cooperating rotatable rolls; of means for driving said rolls to rotate the same; displaceable means for supporting one of said rolls, said means being displaceable laterally away from the other roll from operative position to either one side or the other of the same to separate the rolls; means for locking said displaceable means in position with the rolls in cooperating operative relation; means actuated by movement of said displaceable means in separating the rolls in either of said directions for disconnecting said driving means to stop rotation of said rolls; and manually-operated means for releasing said locking means to permit movement of said displaceable means to effect separation of said rolls.

5. In a wringer, the combination with a main supporting frame; of a roll supported by said frame; a displaceable frame movably mounted on said supporting frame; a roll rotatably supported in said displaceable frame; means for locking said displaceable frame in position with said rolls in cooperating relation; and means for releasing said locking means, including two independently operated, manually actuated members mounted respectively on the supporting and displaceable frames respectively.

6. In a wringer, the combination with a pair of cooperating rolls; of movable means supporting one of said rolls for movement toward and away from the other roll; means for locking said movable means in position with the rolls in cooperating operative relation; and means actuated automatically upon an article being wound around one of said rolls for releasing said locking means to permit movement of the movable means to effect separation of the rolls, said automatically actuated means including a movable abutment member at the side of one of said rolls and adapted to be engaged and moved by said article while being wound on the roll.

7. In a wringer, the combination with a pair of cooperating rolls; of movable means supporting one of said rolls for movement toward and away from the other roll; means for locking said movable means in position; means for unlocking said locking means; and displaceable means in the path of movement of an article being accidentally wound about one of said rolls and engaged by said article for actuating said unlocking means to effect release of said rolls.

8. In a wringer, the combination with a pair of cooperating rolls; of a support for each roll; driving means for rotating said rolls; pressure means carried by one of said supports and cooperating with the roll carried thereby for forcing said roll outwardly of its support toward the other roll; means for limiting movement of said pressure-actuated roll outwardly; means for mounting the support which carries the pressure-actuated roll for movement to shift said pressure-actuated roll toward and away from the other roll; means actuated by movement of said movable support for disconnecting the driving means to stop rotation of the rolls; means for locking said movable support in position with the rolls operatively engaged; and manually-operated means for releasing said locking means to permit displacement of the movable support to release the pressure between said rolls and actuate said disconnecting means to stop rotation of the rolls.

9. In a power-driven wringer for use with clothes washing machines, the combination with a pair of cooperating rotatable rolls; of power-operated means for driving one of said rolls; a swinging support for one of said rolls having its axis of swinging movement substantially parallel to those of said rolls; means for locking said support in position with the rolls in cooperating relation; and means for releasing said locking means to permit movement of said support through the reactive force between said cooperating rolls, said last named means including a manually-operated rocking member mounted entirely on said swinging support and projecting both from the front and rear sides of said support to render the same accessible from either of said sides.

10. In a wringer, the combination with a main frame; of a roll rotatably supported in said frame; a keeper on said frame; a swinging frame

supported above said main frame; a roll rotatably supported in said swinging frame and adapted to cooperate with said first named roll; a sliding latch on said swinging frame engageable with the keeper to center the swinging frame with respect to the main frame; yieldable means forcing said latch into engagement with the keeper; means for locking said latch in keeper-engaging position; and means for releasing said locking means.

11. In a wringer, the combination with a main frame; of a swinging frame supported on said main frame; cooperating rolls carried by said frame; a fixed keeper on said main frame; a movable latch member on said swinging frame engageable with the keeper to latch said swinging frame in centered position above the roll of said main frame; spring means for forcing said latch member into engagement with the keeper; locking means for holding said latch member engaged with the keeper; and means for releasing said locking means to permit said latch member to yield to allow swinging movement of said swinging frame and separation of said rolls.

12. In a wringer, the combination with a fixed frame; of a roll rotatably mounted on said fixed frame; a swinging frame pivotally hung on said fixed frame above said roll for rocking movement in a generally horizontal direction to either side of a vertical plane through the axis of said roll; a second roll rotatably mounted in said swinging frame; keeper means on the fixed frame; a latch member on said swinging frame engageable with said keeper means to center said second named roll with respect to the first named roll; means for locking said latch member in latching relation with said keeper means; a saddle member engaged over said swinging frame and rockable thereon; and means actuated by rocking movement of said saddle member for releasing the locking means.

13. In a wringer, the combination with a pair of cooperating rolls; of means for driving said rolls to rotate the same; power-transmitting means; shiftable gear means for operatively connecting said driving means to the power-transmitting means to rotate said driving means in reverse directions and also to entirely disconnect the power-transmitting means from said driving means; manually-controlled means for actuating said shiftable gear means to shift the same; a swinging support for one of said rolls having swinging movement about a horizontal axis, said support being displaceable to separate said rolls; means for locking said support in position with the rolls in cooperating operative relation; and means automatically actuated by said swinging movement of said support for actuating said manually-controlled means to shift said gear means and disconnect the driving means from the power-transmitting means.

14. In a wringer, the combination with a pair of cooperating rolls; of a swinging frame supporting one of said rolls for movement toward and away from the other roll; means for locking said swinging frame in position with the rolls in cooperating operative relation; means for releasing said locking means to permit swinging movement of said supporting means to effect separation of said rolls; rotary driving means for one of said rolls, including a rotary gear element; power-transmitting means; a shiftable rotary member driven by said power-transmitting means and having bevel gears at opposite ends engageable with diametrically opposite teeth of said

gear element; manually operated means for shifting said rotary member in opposite directions to engage either of said bevel gears with said gear element to rotate the latter in reverse directions; and means automatically actuated by swinging movement of said swinging frame for shifting said rotary member to disengage the bevel gears thereof from said gear element to stop rotation of said rolls independently of manual operation of said manually operated controlling means.

15. In a wringer, the combination with a pair of cooperating rolls; of a swinging frame supporting one of said rolls for movement toward and away from the other roll; means for locking said swinging frame in position with the rolls in cooperating operative relation; means for releasing said locking means to permit swinging movement of said supporting means to effect separation of said rolls; rotary driving means for one of said rolls, including a rotary gear element; power-transmitting means; a shiftable rotary member driven by said power-transmitting means and having bevel gears at opposite ends engageable with diametrically opposite teeth of said gear element; means for shifting said rotary member in opposite directions to engage either of said bevel gears with said gear element to rotate the latter in reverse directions; spring-actuated means for shifting said rotary member to disengage the bevel gears thereof from said gear element to stop rotation of the rolls; means for locking said spring-actuated means in inoperative position; and means automatically actuated by swinging movement of said swinging frame for releasing said locking means from operative engagement with the spring-actuated means to render the latter operative to actuate the rotary member.

16. In a wringer, the combination with a pair of cooperating rolls; of a swinging frame supporting one of said rolls for movement toward and away from the other roll; means for locking said swinging frame in position with the rolls in cooperating operative relation; means for releasing said locking means to permit swinging movement of said supporting means to effect separation of said rolls; rotary driving means for one of said rolls, including a rotary gear element; power-transmitting means; a shiftable rotary member driven by said power-transmitting means and having bevel gears at opposite ends engageable with diametrically opposite teeth of said gear element; means for shifting said rotary member in opposite directions to engage either of said bevel gears with said gear element to rotate the latter in reverse directions; a spring-operated member for shifting said rotary member to disengage the bevel gears thereof from said gear element to stop rotation of said rolls; latch means for holding said spring-operated member in inoperative position; and means automatically actuated by swinging movement of said swinging frame for releasing said latch means to permit operation of the spring-actuated member to shift said rotary member.

17. In a wringer, the combination with a pair of cooperating rolls; of a swinging frame supporting one of said rolls for swinging movement toward and away from the other roll; means for locking said swinging frame in position with the rolls in cooperating operative relation; means for releasing said locking means to effect separation of said rolls; driving means for said rolls; power-transmitting means; shiftable means for con-

necting said driving means with the power-transmitting means and disconnecting the same therefrom to stop rotation of said rolls; manually operated means for controlling the operation of said shiftable means; and means automatically operated by swinging movement of said frame for shifting said shiftable means to disconnect the driving means from the power transmitting means independently of manual operation of said manually operated controlling means.

18. In a wringer, the combination with a pair of cooperating rolls; of a swinging frame supporting one of said rolls for movement toward and away from the other roll; means for locking said swinging frame in position with the rolls in cooperating operative relation; means for releasing said locking means to effect separation of said rolls; driving means for said rolls; power-transmitting means; shiftable means for connecting said driving means with the power-transmitting means and disconnecting the same therefrom to stop rotation of said rolls; spring-actuated means for shifting said shiftable means to disengage the driving means from the power-transmitting means; means for locking said spring-actuated means in inoperative position; and means automatically actuated by swinging movement of said supporting means for releasing said locking means to render said spring-actuated means operative to actuate said shiftable means.

19. In a wringer, the combination with a pair of cooperating rolls; of a swinging frame supporting one of said rolls for movement toward and away from the other roll; means for locking said swinging frame in position with the rolls in cooperating operative relation; means for releasing said locking means to effect separation of said rolls; driving means for said rolls; power-transmitting means; shiftable means for connecting said driving means with the power-transmitting means and disconnecting the same therefrom to stop rotation of said rolls; spring-actuated means for shifting said shiftable means to disengage the driving means from the power-transmitting means; means for latching said spring-actuated means in inoperative position; and means for tripping said latch means to release said spring-actuated means to render the same operative, including a sliding element engageable with said latch means for tripping the latter and fixed cam means on the swinging frame engaging said sliding element to actuate the same during swinging movement of the frame.

20. In a wringer, the combination with a pair of cooperating rolls; of power-transmitting means; driving means for rotating said rolls; shiftable gear means movable to two different operative positions for connecting said driving means to the power-transmitting means to rotate the driving means in reverse directions, and movable to a neutral position to completely disconnect the power-transmitting means from the driving means; manually operated lever mechanism operatively connected to said shiftable means for actuating the same; means normally locked against operation for actuating said lever mechanism and shiftable means, for returning said mechanism and connected shiftable means from either of said operative positions to neutral or disengaged position; a movable frame supporting one of said rolls for movement away from the other roll to separate said rolls and release the same; and means actuated by displacement of said frame for unlocking said means for actuating the shiftable means, thereby releasing the

same to return said shiftable means and lever mechanism to neutral position.

21. In a wringer, the combination with a pair of cooperating rolls; of a swinging frame for supporting one of said rolls for movement toward and away from the other roll; means for locking said frame in position with the rolls in operative relation; driving means for said rolls; and means for releasing said locking means to permit swinging movement of the frame to release the pressure between said rolls, said last named means including a manually-actuated shiftable member having means thereon projecting in the path of an article accidentally wound about one of said rolls to be automatically shifted by engagement with said article.

22. In a wringer, the combination with a pair of top and bottom cooperating rolls; of a fixed frame carrying said bottom roll; a movable frame pivotally supported on said fixed frame above said bottom roll and rotatably supporting said top roll; cooperating latch means on said frames for locking the same together with the top roll centered above the bottom roll; a sliding release bar for releasing said latch means; shiftable cam means cooperating with said bar to move the same to latch-releasing position; a manually-operated rocking member on said swinging frame for actuating the shiftable cam means; and means in the path of movement of an article accidentally wrapped about said top roll and actuated by engagement with said article for automatically shifting said cam means to operate the bar and release the latch means.

23. In a wringer, the combination with a support; of a roll rotatably mounted on said support; a second support; a roll rotatably mounted on said second support for rotation about an axis parallel to the axis of rotation of said first named roll; means for mounting said second named support for movement with respect to said first named support to position the roll carried thereby in opposed relation to said first named roll, with the axes of rotation of said rolls in a common plane, and for movement in reverse directions to displace said second named roll to either side of said first named position to separate said rolls to release the same from operative engagement; means for driving said rolls; and means automatically operated by movement of said second named support to either side of said first named position of said roll for disconnecting the driving means and stopping rotation of the rolls.

24. In a wringer, the combination with a pair of cooperating rolls operating under pressure; of means for driving said rolls; a support for each roll, one of said supports being pivoted on the other for swinging movement, said supports normally supporting the rolls in opposed operative relation with the axes of said rolls in parallel relation in a common plane, said pivoted support being swingable in reverse directions from said normal position to displace the roll carried thereby to either side of the cooperating roll to separate said rolls; and means actuated by said pivoted support in its swinging movement in either direction from normal position for disconnecting the driving means and stopping rotation of said rolls.

25. In a wringer, the combination with a frame having a wringer roll journaled therein; of a support pivoted on the frame on an axis directly above said wringer roll and having a wringer roll movable therewith laterally to either side of the first named wringer roll; means for lock-

ing said support in centered position above said first named wringer roll; means for driving said rolls; means controlled by the operator for releasing said locking means and moving said support to either side of said first named roll to effect separation of said rolls to relieve the pressure therebetween; and means automatically operated by separation of said rolls in either of said directions for disconnecting the driving means and stopping rotation of said rolls.

26. In a wringer, the combination with a fixed frame; of a roll rotatably mounted on said fixed frame; a swinging frame pivotally hung on said fixed frame above said roll for movement on a fixed axis; a second roll rotatably mounted in said swinging frame; means for locking said frame members together with rolls thereof in cooperating relation; a saddle member of inverted U-shaped formation rockably mounted on said swinging frame for movement in a direction transversely of the axes of the rolls; and means actuated by said rocking movement of the saddle member for disengaging said locking means.

27. In a wringer, the combination of a frame having upstanding side members, a wringer head pivotally supported between said members for swinging movement on a horizontal axis, lower and upper wringer rolls carried by said frame and said head respectively, means for latching said head to said frame with said head in a substantially centrally alined position with respect to said frame and with said wringer rolls in cooperative relation, means for yieldably urging said rolls together when the frame and head are thus latched, means for driving said rolls including a shiftable clutch mechanism, and means extending from a side member inwardly into the path of swinging movement of said head as said head moves in either direction from its latched position for engagement by said head to shift said clutch mechanism to its neutral position.

28. In a wringer, the combination of a frame having upstanding spaced side members, a hollow head pivotally mounted between said members, cooperating wringer rolls respectively carried by said head and said frame and having a cooperating relationship when said head is vertically alined with said frame, means for urging said rolls together when the frame and head are alined, and latching means for holding the head in alined position including latches carried by said head for engagement by said frame, means located within said head for maintaining said latches operatively engaged, and means for actuating the latch maintaining means to release said latches comprising a leverage increasing mechanism mounted in said head and operatively associated with the maintaining means, and a manually manipulative member mounted externally of said head and connected with said mechanism.

29. A wringer comprising, in combination, a lower frame section, an upper frame section pivotally connected to said lower section for swinging movement on a horizontal axis, cooperating wringer rolls mounted on said upper and lower sections, means for creating operative pressure between said rolls releasable upon swinging movement of said upper frame section out of a centrally alined position, and means for latching said sections in alined position including vertically slidable latches on said upper section, means on said lower section engageable by said latches, spring means for urging said latches toward such engagement, a horizontal slide carried by said upper section to extend across the upper ends

of said latches and prevent disengaging movement thereof, said slide having apertures therein disposable upon endwise movement of said slide to receive the ends of said latches and permit upward disengaging movement thereof, means manipulable by the operator for retracting said slide to position the apertures opposite the latch ends, and means providing an engagement between the retracted end of the slide and the lower frame member for preventing return movement of the slide while the frame sections are out of alinement.

30. In a wringer, the combination of upper and lower frame sections pivotally joined for relative movement of the upper section on a horizontal axis in either direction from an intermediate alined operative position, wringer rolls carried by said sections for cooperative engagement when the said sections are alined, means on said lower section engageable by said latch means, the latched interengagement being releasable by a force tending to swing the upper section out of said alined position, a member carried by said upper section to engage and hold said latch means against releasing movement, and means conveniently positioned for actuation by the user for moving said member out of engagement with said latch means.

31. In a wringer, the combination of upper and lower frame sections pivotally joined for relative movement of the upper section on a horizontal axis in either direction from an intermediate alined operative position, wringer rolls carried by said sections for cooperative engagement when the said sections are alined, roll pressure applying means releasable upon movement of said upper section out of said alined position, retractable latch means mounted on said upper section, means on said lower section engageable by said latch means when said sections are alined, the engagement being releasable by such relative movement of the upper section as would be induced by the coaction of the rolls during rotation, a member mounted for movement into and out of engagement with said latch means to prevent or permit release of said engagement, and a manipulable lever engaging said member to move it out of engagement with said latch means.

32. In a wringer, the combination of upper and lower frame sections pivotally joined for relative movement of the upper section on a horizontal axis in either direction from an intermediate alined operative position, wringer rolls carried by said sections for cooperative engagement when the said sections are alined, means for applying pressure to said rolls, retractable latch means on said upper section, means on said lower section engageable by said latch means when said sections are alined, the engagement being releasable by relative movement of the upper section, a member engageable with said latch means to prevent retraction thereof, a manipulable lever engaging said member to move it out of engagement with said latch means, and means for maintaining said member out of engagement with said latch means while said frame sections are out of alinement.

33. In a wringer having, in combination wringer rolls, pivotally connected frames supporting said rolls, means for applying pressure to said rolls when the rolls are operatively en-

gaged, and releasable means for connecting said frames to maintain said rolls in operative engagement, one of said frames upon disengagement of said releasable means having swinging movement effective to separate said rolls, means for driving said rolls including a disengageable clutch manipulable into and out of roll driving condition independently of the frames when said frames are connected, and means engageable by the swingable frame only if said clutch is engaged for moving said clutch to its disengaged position when the swingable frame is released for movement.

34. In a wringer, the combination with a pair of relatively swingable frame sections, a pair of cooperating rolls supported by said frame sections for movement into and out of cooperative relation by the swinging movement of said frame sections; of means for releasably holding said frame sections with said rolls in operative relation; power-transmitting means; driving means for rotating said rolls; shiftable gear means movable to two different operative positions for connecting said power-transmitting means to the driving means to rotate the latter in reverse directions, and movable to a neutral position to completely disconnect the power-transmitting

means for the driving means; manually-operated means for actuating said shiftable gear means; and means automatically operated by release of said frame sections for swinging movement for shifting said manually-operated means to neutral position to release the driving means from the power-transmitting means and stop rotation of said rolls.

35. In a power driven wringer, the combination with a pair of cooperating rotatable rolls; of power operated means for driving one of said rolls; movable means for supporting one of said rolls for movement toward and away from the other roll; means for locking said movable means in position with the rolls in cooperating operative relation comprising a fixed keeper, a movable latch member engageable with the keeper, and a member for locking said latch member in engaged relation with the keeper; and manually-operated actuating means mounted entirely on said movable means for releasing the locking means to permit disengagement of said latch member from the keeper and free said supporting means for movement by the relative rotation of said cooperating rolls to separate said rolls.

SIMON E. SCHROEDER.
